UNITED STATES PATENT OFFICE.

DEWITT C. BOWEN, OF KANSAS CITY, MISSOURI.

DESIGN FOR A BRACKET.

SPECIFICATION forming part of Design No. 25,203, dated February 25, 1896.

Application filed October 5, 1895. Serial No. 564,807. Term of patent 7 years.

To all whom it may concern:

Be it known that I, DEWITT C. BOWEN, of Kansas City, in the county of Jackson and State of Missouri, have invented and produced 5 a new and original Design for a Bracket, of which the following is a full, clear, and exact description.

Reference is to be had to the accompanying drawings, forming a part of this specification, 10 in which—

Figure 1 represents in perspective a bracket embodying my new design, and Fig. 2 is a vertical section.

The leading feature of my design resides in 15 the bracket of substantially X shape, the members being curved and terminating in horizontal surfaces at top and bottom.

Minor features of the design reside in the top and bottom horizontal surface, being offset or disposed in planes respectively above 20 and below the terminal ends of the convexed back surfaces of the bracket members, the bracket thus presenting small surfaces between the said convexed surfaces and the horizontal surfaces. 25

I claim—

The design for a bracket herein shown and described.

DEWITT C. BOWEN.
